UNITED STATES PATENT OFFICE

JEAN COTAL, OF PARIS, FRANCE, ASSIGNOR TO SOCIETE D'EXPLOITATION DES BREVETS
COTAL, OF PARIS, FRANCE

ELECTROMAGNETIC CLUTCH

Application filed April 8, 1929, Serial No. 353,551, and in France April 26, 1928.

With the known electro-magnetic clutches it is very difficult in practice to start a vehicle suitably and without shocks by progressive magnetic adhesion, as the air-gap between the electro-magnet and its armature cannot be kept sufficiently small and constant to provide for the clutch contact with a small initial exciting action, such as is necessary to actuate the apparatus in a progressive manner, for in fact the initial air-gap becomes greater and greater, and in a short time the apparatus must be energized to such a degree that a violent contact is the result, so that the parts are drawn forward in an abrupt manner, and the whole driving gear will be thus subject to severe shocks.

The invention relates to a special clutch device assuring a constant and well-determined air-gap between the electro-magnet and its armature.

The accompanying drawing shows by way of example a longitudinal section of a constructional form of the clutch according to the invention as applied to a speed changing device.

To the driving shaft 1 is secured an electromagnet 2 whose respective armature 4 is secured to a toothed wheel 6.

The clutch device comprises a ring 33 which is slidable by easy friction in the interior of the armature 4, and suitable springs 34 urge the said ring with a sufficient pressure against the internal shoulder 36 of the armature 4.

The ring 33 comprises an annular projection 37, which makes contact with a corresponding annular projection 38 on the electro-magnet 2, and this contact takes place at a light pressure produced by a spring 35 whose tension is distinctly less than the sum of the tensions of the said springs 34, and thus when in the inoperative position, the said projections 37 and 38 will be in contact due to the action of the spring 35, and the said shoulder 36 of the armature 4 is urged by the springs 34 against the ring 33, thus assuring an air-gap of a few tenths of a millimeter between the said armature 4 and its electro-magnet.

Under a weak exciting action, the armature 4 is at once attracted by the electro-magnet 2, thus compressing the springs 34, since the air-gap has but a very small magnetic resistance.

When the exciting action ceases, the armature 4 is brought back by the springs 34 and again makes contact with the ring 33, thus forming with the electro-magnet 2 an air-gap of a well-determined value. The wear produced between the contacting surfaces of the armature 4 and of the electromagnet 2 and which has the tendency to increase the distance between the armature 4 and the electromagnet 2 in the inoperative position is compensated by the wear produced between the projections 37 and 38 and causing the ring 33 and consequently the armature 4 to be brought nearer the electromagnet 2. The members 6, 4, 33 and 34 are always rotated as a whole about the axis of shaft 1, so that no appreciable wear is produced between the ring 33 and the shoulder 36.

Having now described my invention what I claim as new and desire to secure by Letters Patent is:

1. An electro-magnetic clutch comprising a driving rotatable shaft, an electromagnet carried by said driving shaft, an armature for said electromagnet rotatably mounted coaxially with relation to said driving shaft, means for guiding said armature towards and away from said electromagnet, a stop member, means adapted to hold said stop member in a fixed position with relation to said electromagnet, and yielding means adapted to urge said armature against said stop member.

2. An electro-magnetic clutch comprising a driving rotatable shaft, an electromagnet carried by said driving shaft, an armature for said electromagnet rotatably mounted coaxially with relation to said driving shaft, means for guiding said armature towards and away from said electromagnet, a stop member, yielding means adapted to hold said stop member in a fixed position with relation to said electromagnet and yielding means adapted to urge said armature against said stop member.

3. An electro-magnetic clutch comprising a driving rotatable shaft, an electromagnet carried by said driving shaft, an armature for said electromagnet rotatably mounted coaxially with relation to said driving shaft, means for guiding said armature towards and away from said electromagnet, a stop member, yielding means bearing at one end on said stop member and at the other end on one side 10 of said armature, whereby said armature is urged against said stop member, and other yielding means of less strength than said first mentioned yielding means bearing on the other side of said armature, whereby said 15 stop member is held against said electromagnet.

In testimony whereof I have signed my name to this specification.

JEAN COTAL.
